CONVEYER

Harry D. Lathrop, Chicago, Ill., assignor to The Lathrop-Paulson Company, Chicago, Ill., a corporation of Illinois

Application June 5, 1939, Serial No. 277,529

4 Claims. (Cl. 198—189)

This invention relates to a conveyer, and more particularly to conveyer links which are brought together in overlapping relationship.

Great difficulty has been encountered in the handling of drums or barrels which are equipped with thick metal bands which extend outwardly for some distance from the body of the drum or barrel. The protruding metal forms a hook which engages portions between the links, and in the movement of the links under the barrel tends to twist, distort, and wear the links. Single conveyer links equipped with laterally extending flanges have been extremely unsatisfactory because the flanges are engaged by the protruding metal bands or hooks of the drum. For this reason, it has been felt necessary that a pair of parallel link conveyers be employed, a structure which is very expensive both in construction and in operation.

An object of the present invention is to provide a conveyer formed of a single series of chain links which is adapted to handle barrels, drums, boxes, and other products equipped with projections or extensions whereby the same can be supported upon a relatively narrow link while at the same time slippage thereof on the links does not twist or distort the links. Other specific objects and advantages will appear as the specification proceeds.

The invention is illustrated, in a preferred embodiment, by the accompanying drawing, in which—

Figure 1 is a front view in elevation of a link embodying my invention; Figure 2, a bottom plan view; Figure 3, a rear view, with the link inverted; and Figure 4, a longitudinal sectional view showing a pair of links connected together with the inclined supporting webs thereof in overlapping relation.

In the illustration given, the link consists of a main body 10 provided at its forward end with an integral neck extension 11 and a semi-spherical ball 12 carried at the forward end of the neck. At the rear of the neck portion 10 is an open portion 13 which is cut-away to reduce the weight of the link. At the rear of the opening 13 is a socket portion 14 adapted to receive the semi-spherical ball 12 of an adjacent link. Communicating with the socket 14 and flared rearwardly is a neck opening 15 through which the neck of the following link is free to swing laterally.

Integrally formed with the top portion of the link body 10 is a load supporting surface 16 provided with laterally extending wing portions 17. It will be observed that the surface 16 and the

wings 17 are both inclined upwardly and rearwardly, as shown more clearly in Figure 4, and that both project quite some distance to the rear of the body 10. In fact, the rearwardly extending portions of the members 16 and 17 extend over not only the spherical ball 12 and neck portion 11 of the link therebehind but also over a portion of the body 10 and the surfaces 16 and 17 of the neck link.

10 The load supporting shelf 16 and the wings 17 clear the body 10 of the link following, and there is sufficient play between them and the corresponding portions of the following link to enable the two links to be turned laterally with respect to each other, thus permitting the chain to pass about curves, etc.

In the operation of the conveyer, the barrel or drum is placed upon the supporting shelves 16 of the links and is stabilized and confined thereon by the arms or wings 17. When the chain is driven, there is a tendency for the drum with its heavy bands to slide upon the links. In the usual operation of the chain, the ball portion travels ahead of the socket portion, with the result that the wings which are inclined upwardly and rearwardly tend to check the sliding movement of the drum rearwardly relative to the links.

The sliding drum, however, does not strike any projecting part of the links. Instead, the drum is free to slide over the overlapping connections between links, and then when its inertia is overcome, it is carried forward by the conveyer.

With the very simple new structure described, kegs and barrels of the type employing heavy 35 projections can be readily handled upon a single conveyer chain. The slightly upwardly inclined surfaces of the links serve two important functions. First, they tend to check excessive rearward movement of the drum. Secondly, they enable the rearwardly projecting portion of one link to clear the body of the link therebehind. A continuous load bearing surface entirely above the main link body and above the ball and socket portions of the links is thus provided.

45 While in the foregoing description, I have described a single type of link structure, it will be obvious that this may be changed considerably in detail without departing from the spirit of my invention.

50 I wish it to be understood that I do not desire to be limited to the exact details of construction shown and described, for obvious modifications will occur to a person skilled in the art.

I claim:

55 1. A conveyer comprising a plurality of links

connected together for movement with respect to each other in two planes, each of said links having a rearwardly and upwardly projecting top shelf extending above and overlapping the forward portion of the next following link, each of said shelves being spaced above and clearing the next following link to permit free angular movement of the shelf without interference from the next following link.

2. In a conveyer adapted for turning movement in two planes, a link body having at its rear a socket engaged by a forwardly extending spherical ball carried by another link adjacent the rear of said link body, a rearwardly extending and upwardly inclined top shelf on said first mentioned link extending over and spaced from the forward portion of said adjacent link, said shelf being spaced from said adjacent link a sufficient distance to permit horizontal movement of said shelf with respect to said adjacent link.

3. A conveyer comprising a plurality of links pivotally connected together for movement with respect to each other in two planes, a rearwardly extending and upwardly inclined top shelf on each of said links extending over and spaced from the forward portion of the next following link, each of said shelves being arranged to overlap the next following link by a distance suffi-

cient to cover the front edge of the shelf of the next following link, said distance being insufficient to permit said shelves to interfere with the independent movement of other shelves in a horizontal plane.

4. In a conveyer adapted for turning movement in two planes, a pair of links connected together, each link having a body portion, a forwardly extending neck portion and a ball portion carried by said neck and at its rear a socket portion to receive the ball portion of another link, a rearwardly extending and upwardly inclined top shelf on each of said links covering the body of the same and extending over and spaced from the forward portion of the next following link, said shelf portion including a flat substantially horizontal center section, and a pair of flanges extending laterally from the sides of said center section at an acute angle with respect thereto, each of said portions being arranged to overlap the next following link by a distance sufficient to cover the front edge of the shelf of the next following link, said distance being insufficient to permit said shelves to interfere with the independent movement of adjacent shelves in a horizontal plane.

HARRY D. LATHROP.
